UNITED STATES PATENT OFFICE.

BARNETT DAYTON AUSTIN, OF ROME, TENNESSEE.

HORSE-DETACHER.

SPECIFICATION forming part of Letters Patent No. 550,150, dated November 19, 1895.

Application filed January 30, 1895. Serial No. 536,752. (No model.)

To all whom it may concern:

Be it known that I, BARNETT DAYTON AUSTIN, a citizen of the United States, residing at Rome, Smith county, in the State of Tennessee, have invented a new and useful Harness and Shaft-Coupling for Use on Vehicles, as shown by the accompanying drawings, forming part of this specification.

The invention relates to safety appliances for driving-harness, and the object in view is, primarily, to enable the driver to detach the animal from the shafts of the vehicle in case he becomes unmanageable or runs away, and, incidentally, to simplify the harness and dispense with whiffletrees and traces. The preferred construction whereby these objects are attained is illustrated in the accompanying drawings, wherein—

Figure 1 is a plan view of the front portion of a vehicle and its shafts, showing the manner of applying the invention for use. Fig. 2 is an enlarged perspective of that portion of the device that forms part of the harness proper. Fig. 3 is a similar view of a fragment of one of the shafts, showing that part of the device that is secured to the shafts and which serves to releasably attach the device shown in Fig. 2. Fig. 4 is a plan view of the part of the shaft shown in Fig. 3, the immediate parts forming my invention being sectioned horizontally.

In the views like letters and numerals of reference denote corresponding parts.

Referring to Fig. 2, B denotes a buckle-frame. This device forms the means of connection between the harness proper and the vehicle-shafts and is constructed substantially as follows to adapt it for detachable connection to the several draft parts of the harness: b is the central or body portion, and from this project three arms b' b² b³, the arm b' extending in a vertical direction for connection with the strap leading down from the harness-saddle, and the arms b² and b³ extending horizontally, the former toward the front for connection with the strap leading from the hames or breast-strap (as the case may be) and the latter toward the rear for connection to the breeching-strap.

It is characteristic of the invention that no traces or whiffletree are required, the only

means of connection between the harness and the shafts being the above-described buckle-frame and a releasable latching device secured to the shafts, which will be presently described.

The several arms of the buckle-frame B may be provided with independent buckles of ordinary construction for attachment to their respective harness-straps. I prefer, however, to adapt them for such connection in the manner illustrated in the accompanying drawings, as follows:

ff are flanges extending along the edges of the arms, and 244 are guards spanning the space between the flanges at the ends of the arms and raised somewhat above the surface of the arms and the body portion of the buckle-frame, so as to permit the harness-straps to be slid into the arms under the guards and between the flanges. To secure the straps in position each of the arms is provided with a spud 3 to enter the holes in the straps.

As shown in the present drawings, the hame or breast-strap is continuous with the breeching-strap, and the strap leading down from the saddle is continuous with the shaft-girth; but of course these may, if preferred, all be separate pieces, as is usual in ordinary harnesses. I prefer the arrangement shown for convenience, simplicity, and neat appearance.

The construction thus far described adapts the buckle-frame for connection to the harness, of which it forms an essential but detachable part.

To adapt the frame for attachment to the shafts when it is desired to "hitch up" the horse, it is provided centrally with two outwardly and horizontally projecting ears or lugs d d, and in these ears is vertically pivoted a loop or bail s, so that it may swing loosely in a fore and-aft-direction. This completes the construction of the buckle-frame. If desired, it may have an additional arm extending downwardly in line with the arm b' for connection to the shaft-girth; but I deem this unnecessary, as the girth-strap, if not continuous with the saddle-strap, may simply be run up into the arm b' along with the saddle-strap.

The part of the invention that is a fixture to the shafts of the vehicle is as follows:

There is one for each shaft; but as they are identical a description of one will suffice for both.

Referring to Figs. 3 and 4, A denotes a metallic casing, the shape and exterior outline of which are immaterial. This casing is secured to the inner side of the shaft at the point opposite where the saddle-girth of the harness comes, and may be secured by any suitable means, a convenient arrangement being shown in the drawings, where *a a* indicate outwardly-projecting lugs adapted to fit over and under the shaft, partially embracing the same and secured by screws or bolts and nuts. A notch *a'* is made in this casing at any suitable point between its ends, the open end of the notch standing inward or toward the animal. Just back of this notch a latch *l* is pivoted in the casing, so that its free end extends over and closes the notch *a'*. The latch has a rearward or heel extension *a²*, that co-operates with a bolt *e* to form a positive lock. This bolt is slidingly mounted in the casing and has its rear end projecting outside the casing, as shown in Fig. 4. At the front end the bolt has a head *h* with a curved end *h'* abutting against the hub of the latch and a flat side *i* fitting the under side of the heel of the latch, and the opposite side of the head is preferably inclined, as shown at *i'*, co-operating with an inclined surface *i²* on the casing to insure its proper engagement under the heel of the latch. An important function of the curved end of the head *h* is that when the bolt is withdrawn and the latch opened the heel *a²* will be caught on the curve and the latch held open, as indicated in dotted lines in Fig. 4, but in a manner to permit its easy closing without having to again withdraw the bolt. For the purpose of automatically locking and keeping the bolt locked its shank is encircled by a coiled spring *t*. (See Fig. 4.) The construction being as thus described, it will be understood that when the swivel *s* engages the notch *a'* and the latch *l* is locked the harness, and of course the horse, is securely hitched to the vehicle, and the latching devices being rigidly secured to the shafts and the buckle-frame carrying the swivel being an integral part of the harness the fastening has abundant strength for all ordinary draft purposes.

In order to permit the horse to be instantly detached from the shafts in case of runaway or becoming otherwise unmanageable, I at-

tach to the end of the bolt *e*, that projects out of the rear end of the casing A, a cord or strap *F*, and I extend this cord back to a point within easy reach of the driver, arranging it preferably as shown in Fig. 1—that is to say, a continuous cord extending from the bolt on one shaft back loosely around the dashboard to the bolt on the other shaft.

Having thus described my invention, what I claim, and desire to secure by Letters Patent, is—

1. The combination with a harness, of a buckle-frame having an upwardly projecting member adapted for attachment to the saddle straps, forwardly and rearwardly extending horizontal members, adapted, respectively, for attachment to the hame or breast-strap and the breeching strap, and a pivoted loop, bail, or swivel for connection to the vehicle shaft; substantially as described.

2. A buckle-frame for attachment to a harness, consisting of the body portion *b*, the upwardly projecting arm *b'*, with spud 3 and guard 2, and the forwardly projecting arms *b²*, *b³*, with spuds 3 and guards 4 and the pivoted loop, bail, or swivel *s*; substantially as described.

3. The combination of the casing A, adapted for attachment to a vehicle shaft, the notch *a'* in said casing, the pivoted latch *l* having the heel extension *a²* and serving to close the notch when locked, and the releasable sliding bolt *e*, said bolt having the head *h* co-operating with the heel extension of the latch, and projecting at its opposite end through the rear end of the casing, and encircled by the coiled spring *t*; substantially as described.

4. The combination, to form a horse detacher, of the notched casing A, adapted for attachment to a vehicle shaft, and having the pivoted latch *l* serving to close the notch when locked, and the releasable spring bolt *e* acting to lock the latch in closed position, with the buckle-frame B, adapted for connection with harness straps leading from the saddle, the shaft-girth, the hames or breast-strap, and the breeching, and having the pivoted loop, bail, or swivel *s* adapted to fit the notch in the casing; substantially as described.

BARNETT DAYTON AUSTIN.
